FIRE EXTINGUISHING GRENADE

Gino Finzi, Rome, Italy

Application April 6, 1935, Serial No. 15,125
In Italy March 18, 1935

10 Claims. (Cl. 169—28)

The present invention relates to fire extinguishing grenades which are designed to be thrown, manually or otherwise, onto a fire, whereupon the bursting of an explosive charge, generally centrally located in the grenade, generates an internal pressure which breaks the container and sprays the extinguishing charge, consisting either of solid substances preferably in the form of powders, or of liquids, around the neighboring 10 vicinity.

One of the disadvantages of the grenades previously in use is the fragility of their casings or containers; a fragility which has been necessary to their proper operation, but which frequently 15 results in the casing, when it falls on the fire, becoming impaired or partially broken. The internal pressure developed by the deflagration of the bursting charge naturally follows a path of least resistance so that if the casing has been 20 weakened in any spot, the extinguishing effect is likewise weakened.

The inconvenience is still greater when the extinguishing agent is a liquid which can escape through fractures before the operation of the 25 grenade.

To prevent this possibility of damage to the grenade, it has previously been suggested to protect the container with external adjacent layers of a thick substance, for instance strong pasteboard, but this expedient has proved undesirable 30 in that the reinforcement serves as an obstacle to the scattering of the extinguishing charge, so that a larger explosive charge must be used, as a result of which the handling and throwing of 35 the grenade is dangerous.

The present invention is directed to an extinguishing grenade which differs from the prior art grenades, and which avoids the aforementioned disadvantages, which ensures the safety 40 of its handlers and which ensures the greatest certainty of its operation and its extinguishing efficiency. My grenade is provided with a bursting charge contained in a spherical or spheroidal-shaped cartridge i. e. an approximately bulbous 45 shape, having previously arranged rupture lines, said cartridge being located at the centre of the grenade, and being tightly fitted on the usual internal, axial, tubular rod of the conventional grenade, the usual fuse being arranged within said 50 hollow rod and communicating with said bursting charge through convenient vents provided in the tubular rod. Said tubular rod, which serves as a supporting armature for the grenade, is formed of a material capable of mechanically resisting 55 all the strains the rod is exposed to during all the

operations of shaping, charging and mounting the grenade; and at the same time the rod constitutes an absolute protection for the fuse contained in the rod, the proper operation of this fuse thus being ensured for a long time after the 5 construction of the grenade.

A spherical or spheroidal-shaped cartridge for the bursting charge has been chosen instead of a cylindrical cartridge because a container of cylindrical shape has walls which present too 10 great a range of resistance to the deflagration with the result that there are created a plurality of zones between which zones there is a varying intensity with which the extinguishing charge is sprayed, so that there is a non-homogeneous extinguishing effect. The axial armature tube of the grenade, owing to its central location as regards the bursting charge, is subjected to oppositely directed pressure which balance each other in every direction and which prevent the projection 15 of the charge. The ends of the axial armature tube are provided with concave or convex disc-shaped members of a material which is neither metallic nor liable to splinter, such for example as cardboard, papier mache and the like, these members keeping the tube in place, and completing and closing the casing or container of the grenade. The casing preferably consists of a thin, light, non-splinterable moistureproof 20 material, which has been provided with numerous previously arranged rupture lines, whereby, when the grenade is fractured, homogeneous scattering 25 of the extinguishing charge is secured in all directions from the centre of the grenade toward the exterior, under the impelling action of the pressure developed by the bursting internal explosive 30 charge.

That part of the priming fuse which projects out of the container through the axial tubular armature rod of the grenade is protected by a 35 tight case of a moisture-proof material, which, being highly inflammable at the ambient temperature (or temperature of dark heat) or when subjected to the flame itself, is soon ignited, the ignition being immediately extended to the fuse of the bursting charge. This case, for certain purposes, may be provided with filament-like extensions of variable length so that the ignition of the fuse may be quickened when desired.

The container of the grenade may be a polyhedron of any desired shape, and may be provided with a shaft, handle, or shackle for being hurled or suspended. Because of the fragility 40 of the container of the grenade, with its previously arranged rupture lines (a fragility which 45

is necessary for the proper operation of the grenade) an external basket protecting against shock has been provided, this basket being disposed at a certain distance from the container 5 and consisting of a network formed with wide meshes composed of protecting rod-like elements connected at the ends, and having supporting hoods serving as a base, the network also being provided at the extremities of the internal tubular rod of the grenade. The network is made of a light, non-metallic material not likely to splinter, such for example as rubber, paper or cardboard hardened in any desired manner, or a textile material impregnated with 15 suitable plastic masses. This material may also be fixed to other points of the container's surface, forming curved, elastic and deformable elements constituting a safe shock-absorbing device protecting the container should the grenade 20 be dropped accidentally. The hoods preferably are provided with openings for the free passage of the extensions of the inflammable case of the bursting charge. The rod-like elements of the 25 said network, due to their distance from the container and their convenient reduced section, interpose no obstacle to the homogeneous scattering of the extinguishing charge. In addition to the fuse already mentioned, a second fuse may be provided in order to ensure even more the 30 proper functioning of the grenade. The second fuse may be of desired type, and preferably is associated with a time control device, said second fuse with its corresponding time controlling device always being arranged coaxially with 35 the first fuse, but at the other end of the central tubular rod.

This sort of friction ignition control demands a design of the fulminating cap such that sufficient resistance is offered to support the tension 40 (several kg.) necessary to unwind at certain speed the friction spiral on the fulminating substance. This resistance is not presented when the fulminating cap is located on flexible materials, for instance on the end of fuse tubes made 45 of cardboard or celluloid which, in turn, bear on rigid elements, whereby there is the possibility that the fulminating cap may recede from the match just an instance before ignition, so that the functioning of the grenade fails. My 50 arrangement, on the contrary, of the control in the only resistant member of the grenade, i. e. in the armature axial central rod, ensures the immobility of the parts and consequently their invariable functioning, as in the case of a fire 55 arm.

By my invention it is possible to construct a grenade of any desired shape, which grenade has a handle, and which is provided with two fuses for the bursting charge, one of which is heat-controlled, and the other of which is time-controlled by means such as a laniard to be pulled with a jerk. Both fuses are always arranged coaxially within the tubular rod constituting the internal supporting armature of the container 65 forming part of the grenade. This armature rod is provided with radial vents in communication with the bursting charge which preferably is contained in an annular, spheroidal or ovoidal-shaped cartridge adapted to be slipped 70 on the armature rod, which extends along the major axis of the grenade, and which cartridge is preferably disposed approximately midway of the vertical extent of said rod. The tubular rod extends externally of the container into said 75 manoeuvring shaft, which is formed as a pro-

longation of said rod, this shaft preferably being perforated longitudinally in order to allow the passage of the laniard of the time fuse, which is to be pulled at the moment of ignition, the laniard being shown as terminating in a 5 ring or hook.

Other grenades may be without shafts but with the same fuses as above mentioned, either one or both, the shaft being replaced by a hood having openings the hood preferably being constructed of a material not likely to splinter. The wood serves to fix the network and the pulling device for the time fuse, and it may also be utilized to allow the passage of the eventual filament-like extensions in the instance where the fuse is of the thermal type. The grenades will be provided with a launching and suspension handle or shackle made of a suitable flexible light material, the said handle or shackle being connected in any desired manner to either or both of the container and the protecting network of the grenade. The handle or shackle may also be formed of one or more elements of the protecting network or basket and projections therefrom. 10 15 20 25

In order to illustrate the advantages of the grenade according to my invention both when provided with a shaft or flexible shackle and when there is no shaft, the grenade in the last-mentioned case always being equipped with the 30 protecting network, two modifications will be described in connection with the accompanying drawings in which the same parts are indicated by the same reference numerals.

In the drawings, Fig. 1 is an axial section of the extinguishing grenade, having a manoeuvring shaft provided with two fuses, one thermal, the other time-controlled, the latter being of the type provided with a laniard to be pulled with a jerk immediately before the grenade is thrown into 40 the fire. The grenade is illustrated without the 45 protecting network. 35 40 45

Fig. 2 is an axial section of an extinguishing grenade which has no shaft and which is particularly fitted for launching, it being provided with a flexible launching or suspension shackle, with two fuses for the bursting charge, one with thermal control and the other with time control of the type having a laniard to be pulled with a jerk when the grenade is launched; both control devices being coaxially arranged in the same tube 50 in a manner similar to that illustrated in Fig. 1. 55

In Fig. 1 the supporting axle or armature of the grenade consists of a tubular rod 1 of convenient material, the upper end 2 of which is externally threaded to cooperate with a double nut 3 which fixes in position the cover 4, the latter being made of a non-metallic, non-splinterable material, and serving to close the top of the container 5 of the grenade, the said container being provided with previously arranged lines of rupture, not illustrated. The lower end of the rod 1 is flared as at 6 and is threaded at 7. The flared end 6 has a flange 8 supporting the bottom cover 9, and this flange bears, by means of its outer surface, 65 and preferably through the intermediary of a washer 10, on the longitudinally bored shaft 11 made of wood or other suitable material and which is threaded or otherwise secured to a perforated connection 12 of convenient material, 70 which connection 12 is threaded or otherwise secured to a central bore in the flaring end 6 of the tubular rod 1, a composite unit thus being obtained which can be easily assembled and taken to pieces, so that when the grenade is already 75 80 85 90 95

charged and is ready for use, there can be installed the time-controlled fuse of the type having a laniard to be pulled when the grenade is about to be thrown, and which operates on a fulminating friction cap 13, the friction spiral 14 of which extends through the connection 12 and shaft 11, to a thread 15 which terminates in the manoeuvring ring 16. When the detonating cap 13, with its friction spiral 14 extending to cord 15 of the 10 friction time fuse, is arranged in the tube 1, it is in immediate contact with the safety match 17, which is of the slow-combustion type, so that when it is ignited by the friction cap 13, an appreciable time is required for transmitting the ignition 15 to the fuse match 18, the deflagration of which, when it reaches the vents 19, ignites the bursting charge 20 contained in the cartridge 21, which cartridge, which is spherical or of any other desired shape, is so fixed on the tubular 20 rod 1 that the vents 19 are centrally arranged. The fusing match 18, whose lower end is in contact with the safety match 17, extends through the tubular rod 1 beyond the vents 19, the end 2 of the rod 1 projecting beyond the container 5, 25 this end 2 being externally threaded, and the match 18 terminating in an end 22 which projects beyond the end 2, and which is completely covered with a tight case 23 preferably formed of a cellulose derivative, and which is moisture-proof, with a very low point of inflammability. This case 23 is shown as provided in its external upper part with priming filaments 24 of the same material, with very low point of inflammability, projecting exteriorly through wide openings 25 of the protecting hood 26. This hood 26 is made of a very light non-splinterable material. The peculiar characteristic of the whole priming system of the bursting charge 20 of the grenade 30 according to my invention lies in the coaxial arrangement within the armature tubular rod of the grenade as well as of the thermal fuse, comprising the filaments 24 of the moisture-proof case 23, and of the fuse match 18, and of the time fuse operated by a pull-controlling device 40 comprising the ring 16 with the pull cord 15, the friction spiral 14, the friction detonating cap 13 and the safety match 17 of previously arranged duration of slow combustion. Should the extinguishing grenade be thrown or launched onto the 45 seat of fire, the protecting network or basket (not illustrated in the drawings) is first to be fixed, on one side to the hood 26, and on the other side to the manoeuvring shaft, for example by means of a convenient fixing ring-shaped member (not shown).

The operation of the above-described extinguishing grenade is very simple and very safe. By holding the grenade by means of shaft 11, the ring 16 of cord 15 is pulled, thus causing the spiral 14 to be unwound. The friction caused by the unwinding of this spiral produces the detonation of cap 13, thereby causing the slow combustion of match 17, for a previously arranged time interval, the grenade then being placed in 50 any desired manner on the seat of fire, the filaments 24 extending out of the openings 25 of the protecting hood 26 thereafter being ignited either by the heat of the fire or by contact with the flames, so that the fuse match 18 is ignited, as a 55 result of which, the fuse, ignited at both ends, transmits the flame through the vents 19 of the tubular rod 1 to the bursting charge 20, which upon deflagrating, bursts the container 5 with its previously arranged rupture lines, and the 60 extinguishing substance is scattered homogeneously over the neighborhood of fire so that the latter is speedily quenched.

Fig. 2 shows a typical extinguishing grenade adapted to be launched without the use of a shaft, and which grenade is provided with network or protecting basket comprising rod-like elements 27 made of non-splinterable flexible material, the container or casing being illustrated as spherical in shape, although of course it may be of any other desired form, the casing in any event being provided with previously arranged rupture lines 28, the internal armature consisting of the same tubular rod 1 as in Fig. 1, constructed of suitable material, and with the same cartridge 21 containing the bursting charge 20, similar to the grenade 10 illustrated in Fig. 1. The internally-threaded, flaring end 6 of the tubular rod 1, which according to Fig. 1 is flush with the perforated shaft of wood or other material, is provided in this case with a small, bored connection 29 for the passage 15 of the pull cord 15 of the detonating friction cap 13 of the time fuse, the wood shaft being substituted by a protecting hood 26a similar to hood 26 protecting the other end zone of the grenade, the 20 protecting network or basket bearing on said 25 hoods and consisting of the rod-like elements 27 of flexible, non-splinterable material, said protecting device serving as a shock absorber. The ring 16 projects through the openings 24 of one of said hoods, preferably the hood 26a; the ring, 30 when pulled, tightening the thread 15 and causing the spiral 14 of the detonating cap 13 to be unwound, so that the time-fuse controlling device functions at the instant the grenade is 35 launched, while through the openings of the other hood 26 the igniting filaments of the thermal fuse project, said filaments being ignited when the grenade falls on the seat of fire or in proximity thereto.

For the purpose of launching, this grenade is 40 provided with a shackle 30 of textile material having a yoke 31 extending all around the grenade in a plane perpendicular to the tubular rod, said shackle also serving for fixing to the surface 45 of the container the protecting rod-like elements 27 of the protecting basket, so that the elements 27 are spring-like and curved, constituting certain shock absorbers for protection, and cooperating together with the two hoods 26 and 26a 50 to protect the container of the grenade against damage when the grenade falls.

The operation of said grenade is similar to that of the grenade illustrated in Fig. 1.

It is obvious that besides the two examples of the invention above disclosed and illustrated in the accompanying drawings, the same principles can be employed in other embodiments without departing from the scope of my invention.

Having now particularly described and ascertained the nature of my said invention and in what manner the same is to be performed I declare that what I claim is:

1. A fire extinguishing grenade comprising an approximately bulbous container or casing, an extinguishing charge therein, a tubular rod, a cartridge containing an explosive charge tightly disposed about said rod, said tubular rod being constructed and arranged to constitute the internal axial supporting armature of the whole assemblage of the extinguishing grenade, igniting fuses for the exploding charge coaxially arranged within said rod, an actuating device for one of said fuses also disposed coaxially within said rod, and a second actuating device for the other of

said fuses cooperatively arranged therewith coaxial with said rod.

2. Fire extinguishing grenade according to claim 1, in which said tubular rod is provided at 5 about its midpoint with radially disposed vents extending from one side to the other, so that when one of said fuses burns its flame is propagated through the vents to the explosive charge whereby the latter is exploded and the extinguishing charge scattered about.

3. A fire extinguishing grenade comprising an approximately bulbous container or casing, a tubular rod constructed and arranged to constitute the internal axial supporting armature of the 15 whole assemblage of the grenade, an explosive charge disposed in a cartridge mounted in an annular manner tightly about said tubular rod near its midpoint, an extinguishing charge surrounding said cartridge, igniting fuses for the exploding 20 charge coaxially arranged within said rod, an actuating device for one of said fuses also coaxially disposed within said rod and a second actuating device for the other of said fuses cooperatively arranged therewith coaxial with said 25 rod, said rod being provided near its midpoint with vents defining a transverse passage through said rod and opening into said cartridge so that when one of the fuses burns, its flame is propagated through the vents to the explosive charge, 30 whereby the latter is exploded, so that the extinguishing charge is scattered.

4. A fire extinguishing grenade comprising an approximately bulbous container or casing, an extinguishing charge therein, a tubular rod disposed along the major axis of said container, 35 disc-like members for completing the surface of said container and tightly closing the container to the exterior, means on both ends of the tubular rod for fixing and positioning said disc-like 40 members thereon, a cartridge containing an explosive charge tightly disposed about the said tubular rod, said tubular rod constructed and arranged to constitute the internal axial supporting armature of the whole assemblage of the extinguishing 45 grenade, igniting fuses for the exploding charge coaxially arranged within said rod, an actuating device for one of said fuses also disposed coaxially within said rod, and a second actuating device for the other of said fuses 50 cooperatively arranged therewith coaxial with said rod.

5. A fire extinguishing grenade comprising an approximately bulbous container or casing, an extinguishing charge therein, a tubular rod, a 55 bored connection at one end of said casing adapted to receive a manoeuvring shaft, a cartridge containing an explosive charge tightly disposed about said tubular rod, said tubular rod constructed and arranged to constitute the internal 60 axial supporting armature of the whole assemblage of the extinguishing grenade, igniting fuses for the exploding charge coaxially arranged within said rod, and a controlling device disposed at one end of said rod for the ignition of the fuse 65 and extending to the exterior through the bore of said connection.

6. A fire extinguishing grenade comprising an approximately bulbous container or casing, an extinguishing charge therein, a tubular rod, a 70 cartridge containing an explosive charge tightly disposed about said tubular rod, said tubular rod constructed and arranged to constitute the internal axial supporting armature of the whole grenade assemblage, igniting fuses for the exploding charge coaxially arranged within said 75

rod, an actuating device for one of said fuses disposed at one end of said rod and operable from the exterior of said casing, one end of the other fuse projecting beyond said rod, a case of material of very low burning point enclosing said last mentioned end, and filament-like extensions of varying length projecting from said case and capable of being ignited at temperatures as low as those prevailing in a dark red fire, and serving to produce the ignition of the fuse within 10 said case.

7. A fire extinguishing grenade, comprising an approximately bulbous container or casing, a tubular rod constructed and arranged to constitute the internal axial supporting armature of the whole assemblage of the grenade, a cartridge, tightly mounted about said rod near its midpoint, an explosive charge in said cartridge, said rod being provided near its midpoint with vents defining a transverse passage through said rod, 15 and opening into said cartridge, fuses extending through said rod and juxtaposed adjacent said vent, one of which projects at one end of said rod and is of the thermal type, and the other of which projects at the other end of said rod and is of the safety type, with a previously fixed duration of burning, an ignition controlling device having a friction detonating cap disposed in said rod in conjunction with said last-mentioned fuse, and a cord projecting from said rod for actuating said detonating cap, the flame of the burning fuses being propagated through said vents to said charge, whereby the latter is exploded and the extinguishing charge scattered.

8. A fire extinguishing grenade comprising an approximately bulbous container or casing, a tubular rod constructed and arranged to constitute the internal axial supporting armature of the whole assemblage of the grenade, an explosive nucleus charge disposed in a cartridge tightly mounted in annular manner about said tubular rod near its midpoint, both the container and the cartridge being provided with previously determined lines of rupture in order to obtain the greatest uniformity in the scattering of the extinguishing charge, an extinguishing charge within said casing, and igniting fuses for the explosive charge disposed coaxially within said rod, an actuating device for one of said fuses also disposed coaxially within said rod, and a second actuating device for the other of said fuses arranged cooperatively therewith and coaxial with said rod, said rod being provided near its midpoint with vents defining a transverse passage through said rod and opening into said cartridge so that when one of said fuses burns, its flame is propagated through the vents to the explosive charge, whereby the latter is exploded thus scattering the extinguishing charge.

9. A fire extinguishing grenade comprising an approximately bulbous container or casing, an extinguishing charge therein, a tubular rod, a cartridge containing an explosive charge tightly disposed about said rod, said tubular rod being constructed and arranged to constitute the internal axial supporting armature of the entire grenade assemblage, igniting the fuses for the exploding charge coaxially arranged within said rod, devices for igniting said fuses cooperatively associated with said fuses and said rod, a protecting cage having wide meshes encircling said container in spaced relation thereto, and shock absorbing supports for mounting said container in said cage.

10. A fire extinguishing grenade comprising an
approximately bulbous container or casing, a
tubular rod constructed and arranged to serve as
the internal axial supporting member of the en-
5 tire grenade assemblage, a cartridge containing
an exploding charge tightly mounted in annular
manner about said tubular rod near its midpoint,
an extinguishing charge in said casing, igniting
fuses for the exploding charge disposed coaxially
10 within said rod, actuating devices cooperatively

associated with said igniting fuses and said rod,
said rod being provided near its midpoint with
vents defining a transverse passage through said
rod so that when one of said fuses burns its
flame is propagated through the vents to the ex-
plosive charge, whereby the latter is exploded,
so that the extinguishing charge is scattered, said
container being formed of light, harmless, non-
metallic material. 5

GINO FINZI. 10
